UNITED STATES PATENT OFFICE.

ERLING HOLTSMARK, OF WHITE PLAINS, NEW YORK.

TUNNELING-MACHINE.

1,200,111.

Specification of Letters Patent.

Patented Oct. 3, 1916.

Application filed April 11, 1916. Serial No. 90,417.

To all whom it may concern:

Be it known that I, ERLING HOLTSMARK, a citizen of the United States, and resident of White Plains, in the county of West-
5 chester and State of New York, have invented certain new and useful Improvements in Tunneling-Machines, of which the following is a specification.

My invention relates to a device for tun-
10 neling in earth, in which a rotary head hav-
ing a curved helical face provided with a
cutting edge placed at the front of a cylin-
drical shield cuts the earth and forces it to
a cylinder fixed concentrically to the axis of
15 the helix at the rear of the head and in-
side the shield, said head and cylinder being
revolved by means of gears and a motor,
and during rotation lifts and discharges the
earth to a hopper by means of radial shov-
20 els fixed to said cylinder, the rotating head
at the same time preventing the earth at the
face of the tunnel from caving in. I attain
these objects by the mechanism illustrated
in the accompanying drawing in which—

25 Figure 1, is a half-vertical section and half-
rear view of the shield and rotary head at
right angles of the axis of the helix and
shield; Fig. 2, is a section through the
shield and the rotary head on the line 1—1,
30 Fig. 1; Fig. 3, is a front view of the rotary
head; Fig. 4, is a sectional view on line
4—4, Fig. 2; Fig. 5, is a section through
one of the lifting shovels on line 3—3.

Similar numerals refer to similar parts
35 throughout the several views.

The head consists substantially of the fol-
lowing parts:—a front steel plate 5, having
a helical curved surface; a rear steel plate
6, of a spherical shape, having its center on
40 the axis of the helix at 8; a rear circular
steel ring plate 7, an inner steel plate cylin-
der 9, and an outer steel band 10, forming
the surface of a frustrated cone, the axis of
which coincides with that of the helix. All
45 these plates are riveted to radial girder 11,
curved and cut to fit the bounds of said
plates.

Between the channel-shaped girders 12,
which are curved as shown in drawing, Fig.
50 3, space is provided for a number of cutting
knives 13, bolted, or hinged to girder 12.
The front surface of said knives form part
of the helical curved surface, the rear sur-
face 14 being curved from the cutting edge
55 to the rear spherical surface, while the third
side rests against the back of the channel

girder 12. The cutting knife 35, next to
the periphery of the head is of a special
shape, being provided with two cutting
edges, one of which is parallel to the axis 60
of the helix and the other radial on the heli-
cal curved plate. It also has two curved
surfaces, 14 and 15, which intersect each
other, 14, curving to the rear, and 15
toward the center of the head. Several 65
sets of these cutting knives may be provided,
each of a different inclination, and in this
way the opening 16, in the head may be
varied to suit conditions. If, for instance,
ground with small bowlders is encountered, 70
it may be desirable to leave a large opening,
while for quicksand the opening may be
made as small as the pitch of the helical
surface. In special cases, when a large ob-
struction is encountered, one or more knives 75
may be removed, or swung back, so as to
make mining of the obstacle possible. The
cylinder 9, is concentric with the axis of the
helix, and extends from the helical curved
surface to the rear, as shown in drawing. 80

The cylinder 17, is also concentric with the
axis of the helix, and is riveted to the ring
plate 7, and provided with a gear-wheel 18,
on the outside, the diameter of the gear-
wheel being large enough just to clear the I 85
beams 19, reinforcing the shield. The radial
plates 20, connecting the outer and inner
cylinders 17 and 9, have side plates 21, and
22, shaped as shown on drawing, forming
large shovels. The inner cylinder has open-
90 ings 23, one for each of the shovels. The
earth falling from the cutting knife into the
outer cylinder 17, will, during rotation, be
picked up by the shovels and fall through
opening 23, into a hopper 24, from where 95

it can be transferred to a car, or belt con-
veyer 34. Cylinder 17, is also at the rear
end provided with a circular ring plate 25,
which prevents the earth from falling out
100 of the cylinder at the rear. For the same
purpose the rear side plates of the shovels
are given a large area. The whole head is
rotated by two motors fixed diametrically
opposite each other to the shield and geared
105 to the large gear wheel 18, around cylinder
17, by the small gear wheel 26. Between the
I beams 19, are rollers 27, which bear against
cylinder 17, alternating with rollers 28,
which bear against the circular ring plate
7; the object of these rollers being to reduce
110 friction when the head rotates. The front
of the head having a helical curved shape

will, since the pitch is small, approach a spherical surface with its center at 8. It will, therefore, be possible to swing the head in any direction about the center 8, without 5 exerting much pressure on the ground, which is of advantage when changing the direction of the tunnel. If pressure is exerted on the jacks of one side of the shield, the head will readily adjust itself to an inclined position. The cone-shaped plate 10, at the periphery of the head, envelops the front of the shield and thus prevents dirt from lodging between the head and the shield. The conical shape also insures clearance for the head when advancing. Theoretically, there will be no skin friction on this plate, and this will give the head a certain amount of freedom when changing the direction of the tunnel. The inner cylinder 15 9, is open in the front, and has on its inner surface finplates 29, forming helical surfaces having a large pitch.

As the earth from the face caves into the cylinder, the finplates 29, will roll it to the 25 rear into a hopper 30, as shown in drawing. The purpose of having cylinder 9, open in the front, is to provide additional means for gaining access to the earth in front of the head. The shield consists of a cylindrical plate 31, reinforced by I beams 19, braced by horizontal and vertical girders, 32. The I beams, besides serving as seats for the bearings of the rollers and gear-wheel, form pockets for the hydraulic jacks, 33.

35 I am aware that, prior to my invention, shields shoved by means of hydraulic jacks have been built of a cylindrical hood reinforced with I beams, and vertical, and horizontal girders. I, therefore, do not claim this; but

I claim:

1. In a tunneling machine, the combination with a shield, of an adjustable head having a helically shaped and substantially closed front surface, said shield and head providing a protected working space, a cutting edge fastened to the head, and means for rotating the head.

2. In a tunneling machine, the combination with a shield, of an adjustable rotating head having a helically shaped and substantially closed front surface, said shield and head providing a protected working space, a cutting edge at a slot in the head, and means for rotating the head.

3. In a tunneling machine, the combination with a shield, of a rotary head having a frusto conical ring enveloping the end of the shield, a helical shaped front face to the head and having a central opening and a cutting edge, and means for rotating the head.

4. In a tunneling machine, the combina-

tion with a cylindrical shield, of a frusto conical ring enveloping the end of the 65 shield, a substantially helical shaped head on the ring and having a radial slot, a cutting edge at the slot, means for carrying off the earth and means for rotating the head.

5. In a tunneling machine, the combination with a cylindrical shield, of a helical head having a central opening, finplates in the central opening; disposing means for the dirt, a frusto conical ring about the edge of the head overlapping the shield and 75 means for changing the position of the axis of said head relative to that of said shield.

6. In a tunneling machine, the combination with a shield, of a frusto conical ring at the outer edge of the shield, a helical 80 shaped head on the ring and having a central opening, a cutting edge on the face of the head and having an adjacent slot, roller bearings within the shield and head, gear teeth, means for driving the gear teeth, 85 shovels for emptying the central opening, finplates in the opening, and receiving means for the dirt from the shovels.

7. In a tunneling machine, the combination with a cylindrical shield, of a helical 90 shaped head having a frusto conical ring overlapping the shield, an inner shell, a cutting edge between the face of the head and the inner shell, a cylinder opening at the front of the head, finplates in the cylinder, 95 shovels radiating from the cylinder and emptying therein, means for receiving the dirt from the shovels, and means for rotating the head.

8. In a tunneling machine, the combination with a shield having anti-friction rollers at its front end, of a head having a helical outer surface, rings within the head and supported by the rollers, a frusto conical ring at the outer edge of the head and 105 overlapping the shield, a cutting edge on the face of the head, and means for collecting the dirt at the rear of the head.

9. In a tunneling machine, the combination with a cylindrical shield, of rollers arranged on radial and horizontal axes 110 around the front end of the shield, a ring bearing on the rollers with radial axis, a cylinder within and supported by the rollers with horizontal axis, a head with a substantially helical shaped front face, and having a central opening, a cutting edge adapted to direct the dirt into the central opening, a cylinder about the opening, dirt directing shovels between the cylinders and communicating with the central cylinder, and a hopper in line with the shovels.

Signed at White Plains, in the county of Westchester and State of New York this tenth day of April, A. D. 1916.

ERLING HOLTSMARK.
